UNITED STATES PATENT OFFICE.

WILLIAM H. PERRY, OF CONCORD, NEW HAMPSHIRE.

DESIGN FOR A MONUMENT.

SPECIFICATION forming part of Design No. 22,373, dated May 2, 1893.

Application filed March 21, 1893. Serial No. 467,075. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing, representing the design.

10 The leading features of my design consist in the particular configuration of the base, the pedestal, and the shaft. The base 1, having four vertical sides terminating at their top in an obtuse frustum 2, of a pyramid. The 15 pedestal 3, has four vertical sides which also terminate in an obtuse frustum of a pyramid, shown at 4. The pedestal 3, may be ornamented on one or more of its vertical sides by a raised tablet, 5, which may be used for 20 inscriptions if desired. The shaft 6, has for the main portion four nearly vertical sides, joined at their bottom to the frustum 4, and terminating at their four upper corners in an acute frustum 7 of a pyramid, the four sides 25 of which are partly covered by the flat ornamental extensions 8, of each of the four sides

of the shaft 6, and mounting the four-sided embossed finial 9.

Another feature of my design is the ornamentation of the sides of the shaft 6, which may consist in a single tablet 10, on each side, which is best designated by a surface of a different character from the other portions, and distinguished therefrom by a border line 11, having the configuration shown, that at their bottom being a convexed arch 12, depending from the center of each of which is a trefoil, 13.

Another feature of my design consists in the ornamentation of the base, pedestal, and shaft by surfaces of a different character. Those 40 surfaces marked by the letter A being termed rockwork, those marked B, hammered work, and those marked C, polished work.

What I claim is—

The design for a monument substantially 45 as herein shown and described.

In testimony whereof I affix my signature in presence of two witnesses.

W. H. PERRY.
